CLAIM

The ornamental design for a combined case and band for smart watch, as shown and described.

DESCRIPTION

FIG. 1 is a right, rear and top perspective view of a combined case and band for smart watch showing my new design.

FIG. 2 is a left, front and bottom perspective view of the combined case and band for smart watch.

FIG. 3 is a front view of the combined case and band for smart watch.

FIG. 4 is a rear view of the combined case and band for smart watch.

FIG. 5 is a left side view of the combined case and band for smart watch.

FIG. 6 is a right side view of the combined case and band for smart watch.

FIG. 7 is a top view of combined case and band for smart watch; and,

FIG. 8 is a bottom view of the combined case and band for smart watch.

The broken lines in the drawings depict portions of the combined case and band for smart watch that form no part of the claimed design.

1 Claim, 8 Drawing Sheets
